DOOR HOLDEE

Michael J. Sasgen, Chicago, Ill.

Application October 13, 1941, Serial No. 414,883

10 Claims. (Cl. 292—275)

This application is a continuation in part of my copending application, Serial No. 342,527, filed June 26, 1940.

This invention relates to door holders of the character effective to hold a door in fully open position or in selected positions intermediate the fully open or fully closed positions thereof.

Those door holders which have been employed heretofore to hold doors as aforesaid and which have been constituted and arranged so as to embody parts respectively secured to the upper portions of a door and jamb have usually relied upon friction between relatively movable parts thereof to retain the door in open positions, and in such instances it has been necessary to move the door against the effect of such friction.

Moreover, those door holders of the aforesaid type as heretofore constructed and which have been effective to retain a door only in fully open position have been so arranged as to always be effective irrespective of whether or not it was desired in all instances to retain the door in fully open position. For example, in those instances where a door has been equipped with conventional door closing means and also with means for retaining the door in fully open position there are instances, such as during inclement weather, where it may not be desired to retain the door in fully open position and in which instances it is desired to have the usual door closing means effective to close the door. However, the usual door closing means are prevented from bringing about closing of the door when the door has been fully opened and such prior devices for retaining the door in fully open position have been used and embody means for holding the door in fully open position and which means become effective to prevent the door closing means from closing the door.

Furthermore, those arrangements of the aforesaid character as heretofore constructed, which have been effective to retain a door in fully open position, have usually been so constituted and arranged that resilient portions included therein might become ineffective to such a degree that the arrangements become ineffective for the purposes for which they were intended.

In view of the foregoing and kindred objections and difficulties which have been encountered, it is among the objects of my invention to so arrange a door holder, embodying parts adapted to be respectively secured to the upper portions of a door and jamb, that the holder will not interfere with opening and closing of the door or cause a friction drag to be impressed upon movements of the door, and other and related objects are to so arrange a door holder of the aforesaid character that it will be effective to either hold a door in fully open position or in positions intermediate the fully open and fully closed positions thereof; to utilize manually operable means for retaining

a door in position intermediate the fully open and fully closed positions thereof; to utilize automatically operable means for retaining a door in fully open position and to enable such means to be manually rendered ineffective when so desired; to incorporate innate resiliency in the door holder so as to mitigate against the effects of shock and the like in the course of use thereof; and to utilize yieldable portions for retaining a door in fully open position and to so arrange such portions that the tension thereof may be expeditiously adjusted when and as required or desired.

While it is advantageous to so arrange a door holder of the aforesaid character that the means effective to retain the door in fully open position may be rendered ineffective when and as required or desired, it is also advantageous so to arrange door holders of the aforesaid character that they may be used with doors which are hinged either at the right-hand or the left-hand side thereof. However, in an instance where the means normally effective to retain a door in open position may be manually rendered ineffective, it is necessary to enable movement of the parts which bring this about to and from effective and ineffective positions, and in such circumstances it is advantageous to so arrange the parts that this movement may be effected in a direction away from the door so as to enable the various parts of the door holder to be so mounted that they will lie in close proximity to the door when the door is fully closed. However, if this is to be realized in a door holder which may be used with either a door hinged at the right-hand or the left-hand side thereof, it is necessary that the parts which are movable as aforesaid be capable of such movement irrespective of whether the door holder is used with a door mounted at the right-hand or the left-hand side thereof, and it is desirable that the parts be conveniently located and be capable of movement in both such circumstances in a direction away from the door and so to do is another important object of my invention.

In instances where manually operable means are employed for securing a door in positions intermediate the fully open and fully closed positions thereof, it is advantageous to prevent undesired displacement of the movable parts of the manually operable means so as to prevent loss of these parts and insure availability thereof when the functioning thereof is desired and to enable this to be accomplished is still another object of my invention.

Yet further objects of this invention are to so arrange relatively movable parts of the door holder that freedom of movement therebetween will be assured at all times; to expedite assembly of the interrelated parts of the door holder and yet insure against undesired displacement of the parts; to facilitate installation of a door holder of the aforesaid character; and to provide

an efficient and positive door holder of the aforesaid character which will be simple and economical in construction, installation and use.

Still another object is to enable my novel door holder to be utilized for the purpose of retaining the door in closed position, and objects ancillary to this are to utilize manually operable means for the purpose of preventing movement, relative to the door and jamb, of a portion of my novel door holding apparatus which so moves when the door is moved from fully closed to an open position so as to thereby enable the door to be retained in fully closed position; and to mount a latching member on the door embodying the part movable into position to prevent movement, relative to the door and jamb, of a rod that is pivotally attached to the door and jamb.

Other and further objects of the present invention will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a perspective view of a preferred embodiment of my invention utilized to retain a door intermediate fully open and fully closed positions thereof;

Fig. 2 is another perspective view of the preferred embodiment of my invention utilized to retain a door in fully open position;

Fig. 4 is a front elevational view of my novel door holder showing the same mounted on a jamb and a door hinged along the left-hand side thereof;

Figs. 5 and 6 are sectional detail views taken substantially and respectively on the lines 5-5 and 6-6 on Fig. 4;

Fig. 7 is a fragmentary side elevational view of a modification of the guide sleeve shown in Fig. 4;

Fig. 8 is a sectional detail view taken substantially on the line 8-8 on Fig. 7;

Fig. 9 is a horizontal view taken substantially on the line 9-9 on Fig. 4;

Fig. 10 is a vertical view taken substantially on the line 10-10 on Fig. 9;

Fig. 11 is a horizontal view, drawn to an enlarged scale, showing interengageable parts of my door holder in the position in which they are effective to retain a door in fully open position;

Fig. 12 is a vertical view somewhat similar to Fig. 11 but showing the parts arranged to be ineffective to retain a door in fully open position;

Fig. 13 is a view similar to Fig. 4 but showing a modified form of my invention;

Fig. 14 is a sectional view taken substantially on the line 14-14 on Fig. 10;

Fig. 15 is a view similar to Fig. 14 but showing the parts in another position;

Fig. 16 is a detailed view taken substantially on the line 16-16 on Fig. 4;

Fig. 17 is a detail view taken substantially on the line 17-17 on Fig. 10;

Fig. 18 is a fragmentary perspective detail view

of one of the interengageable elements illustrated in Figs. 11 and 12;

Fig. 19 is a perspective detail view of a sleeve embodied in my door holder and embodying a part adapted for cooperation with the element shown in Fig. 18; and

Fig. 20 is a sectional detail view, taken substantially on the line 20-20 on Fig. 4, of a modification of my invention operable to retain the door in fully closed position.

The preferred embodiment of my invention illustrated in Figs. 1 to 6, inclusive, Figs 9 to 12, inclusive, and Figs. 14 to 19, inclusive, is effective to retain a door either in the fully open position thereof or in positions intermediate the fully open and fully closed positions thereof and to this end embodies means which are automatically effective to retain the door in fully open position, which may be manually rendered ineffective when so desired, and also manually operable means which are effective to retain the door in positions intermediate the fully open and fully closed positions thereof.

This preferred form of my invention embodies a guide rod 20 which in the present instance is hexagonal in outline, but it is to be understood that any other desired polygonal outline could be employed or, if desired, this guide rod could be circular in outline. However, because of the utilization of manually operable clamping means, as hereinafter explained, it is advantageous to employ a guide rod of such polygonal configuration that a flat face will be presented to a friction clamping portion embodied in the manually operable means. As best shown in Fig. 10, the guide rod 20 is screw-threaded as at 21 at one end thereof for reception in a tapped opening 22 in a lug 23 on an eyelet 24. The eyelet 24 is adapted to neatly fit between the ears of a bifurcated lug 25 of a bracket 26 to which the ear is pivotally connected, either by a rivet as R, Fig. 10, or by a screw as S, Fig. 13. The bracket 26 is secured to the door as D by screws 27 or other suitable securing means.

The guide rod is passed through a complementary-shaped opening 28 in a guide sleeve 29 that is pivotally or swivelly connected to the jamb as J, as will be explained. This guide sleeve has aligned bosses 30 and 31 projected from opposite faces and near one end thereof. The bosses 30 and 31 include aligned bores 32 and 33 and the outer portion of the bore 33 is screw-threaded as indicated at 34. Desirably, a suitable milling tool is passed through the bore 32 and is utilized to cut away a part of the screw threads 34 as at 35 along the wall of the bore 33 at the inner end of such screw threads. Hence, when the screw-threaded portion 36 of a thumb screw 37 is run into the screw threads 34, the inner end of the screw-threaded portion 36 aligned with the cut-away portion 35 may be peened or otherwise rolled over, as indicated at 38, to be disposed in this portion. This arrangement limits the rotative movement of the thumb screw 37 relative to the boss 31 and prevents displacement of thumb screw 37 from the boss 31 for a purpose which will be explained presently.

For the purpose of pivotally connecting the sleeve 29 to the jamb as J, an attachment plate 39 is fastened to the jamb associated with the door as D by wood screws 40 or the like. This plate has a recess 41 in the face thereof adapted to be disposed toward the jamb as J, this recess 41 being disposed about a medially located opening 42 in the plate 39 whereby an annular shoulder 43

is provided on the plate 39. A washer 44, preferably of fibrous or other non-rusting or otherwise non-corroding material, is disposed in the recess 41 and the reduced portion 45 at the free end of the boss 30 is passed through the opening 42 and an aligned opening in the washer 44. Hence, when the free end of the reduced portion 45 of the boss 30 is peened or otherwise rolled over onto the washer 44, as indicated at 46, displacement of the sleeve 29 from the plate 39 is prevented and a pivotal interconnection is afforded between the attachment plate 39 and the guide sleeve 29. The interposition of the washer 44 between the relatively movable parts of this pivotal interconnection insures freedom of movement between these parts at all times.

When the bracket 26 is secured to a door as D and the attachment plate 39 is secured to a jamb as J and the door D is moved from the fully closed position thereof shown, for example, in Fig. 9, the guide rod 20 slides through the sleeve 29 in an amount proportionate to the degree of opening of the door. Hence, by tightly clamping the guide rod 20 in the sleeve 29, the door D may be retained in various positions intermediate the fully open and fully closed positions thereof, the particular position in which the door may thus be retained being dependent upon the amount the guide rod 20 has moved through the guide sleeve 29. Therefore, a fiber button 47 is secured in a pocket 48 in the screw-threaded portion 36 of the thumb screw 37 and projects beyond the free end of such portion and where, as in the present instance, the guide rod 20 is polygonal in outline, the button 47 is arranged to engage a flat face of the guide rod.

Hence, when a door as D has been opened in a desired amount, as shown in Fig. 1, for example, the thumb screw 37 may be grasped and turned to thereby engage the fiber button 47 with the guide rod 20 to thereby clamp in the guide rod in the sleeve 29, as shown in Fig. 3, and in this way the door D may be secured in a desired position. The button 47 is preferably made of fibrous material so as to insure a good friction grip with the guide rod and thereby prevent movement of the guide rod 20 relative to the sleeve 29 when it is desired to retain the door in a selected position intermediate the fully open and fully closed positions thereof or, if desired, in either of these positions. However, when the thumb screw 37 is grasped and turned so as to retract the fiber button 47 from engagement with the guide rod 20, as shown in Figs. 5 and 10, the guide rod may freely move through the guide sleeve without having a friction drag thereon which might impede free movement of the door. It will be recognized that the rolled over portion 38 on the thumb screw 37 is movable in but a limited amount in the cut-away portion 35 and this is effective to prevent displacement and loss of the thumb screw.

The arrangement of the door holder as thus far described enables retention of the door in desired positions to be manually effected and may be advantageously utilized in instances where it is desired to hold a door in such a position as to prevent free passage therethrough and may be utilized, for example, to retain a door in a partly open position so that circulation of air thereby may be afforded but at the same time children and other persons may be prevented from passing through the door opening into a room or the like.

It will be recognized, however, that there are many instances where it is desired to retain, at

least at certain times, a door in fully open position as, for example, the doors leading to shipping and receiving platforms and the doors at the entrance to churches, theaters or the like where, particularly during cold weather and the like, it will be advantageous to keep doors closed most of the time but also where it will be desirable to keep the doors in fully open position to permit free passage thereby. I have therefore so arranged my novel door holder that it will automatically retain a door in fully open position when this is so desired.

Hence, at the end of the guide rod 20, opposite the screw-threaded end thereof, I provide a reduced circular portion 49 to thereby define a shoulder 50. A further reduced circular stem portion 51 projects outwardly from the reduced portion 49 and is screw-threaded as at 52 near the free end thereof. The reduced circular portion 49 affords a bearing for the element generally indicated at 53 and which is fragmentally illustrated in Fig. 18, this element comprising a flat plate 54 which has an opening 55 therein which is sized to neatly fit on the reduced circular portion 49.

A sleeve 56 having a flange 57 at one end thereof is disposed about the reduced stem portion 51 and the outwardly disposed face of the flange 57 engages the adjacent face of the plate 54. A bearing surface 58 is provided in the sleeve 56 at the end thereof whereat the flange 57 is provided and neatly fits on the reduced circular portion 49 so that the sleeve 56 is supported from the portion 49. A coil spring 59 is disposed about 35 the stem portion 51 and engages a shoulder 60 formed in the sleeve 56 near the end thereof whereat the flange 57 is provided. A castellated nut 61 is mounted on the screw threads 52 on the stem portion 51 and tensions the spring 59 40 wherefore this spring acting against the shoulder 60 forces the flange 57 toward the plate 54 to thereby urge the plate 54 into engagement with the shoulder 50 on the guide rod 20. This arrangement also affords a resilient abutment effective to absorb shock when the element 53 engages the guide sleeve 29 which occurs when the door as D is moved to fully open position, this engagement of the element 53 and the guide sleeve 29 being described more fully presently.

50 A pair of resilient fingers 62 and 63 project inwardly from the plate 54 substantially parallel to but in spaced relation with the adjacent portion of the guide rod 20 and the free ends of these fingers are flared outwardly, as best shown 55 in Fig. 11, to facilitate passage therebetween of a projecting end portion E on the guide sleeve 29.

By referring to Figs. 11 and 12 it will be seen that the end portion E of the sleeve 29, which projects toward the resilient fingers 62 and 63, 60 is substantially rectangular in cross section and the sides of this rectangularly extending portion which extend parallel to the walls of the bosses 30 and 31, which is to say, which extend vertically when the attachment plate 39 is secured to a jamb J as shown in Fig. 10, include formed portions afforded, in the present instance, by a pair of outwardly projecting rounded ears 64 and 65 whereas the other two faces, which is to say, the horizontally disposed faces of this projecting end portion E, are substantially flat, as best shown 65 in Fig. 12.

The guide rod 20 is of such length and the attachment plate 39 is secured to the jamb J in such spaced relation with the hinged edge of a door as D that when a door is swung on the

hinges as H therefor from the full-line position thereof shown in Fig. 9 to the broken-line position thereof in this view, which is the fully open position of the door D, the guide rod 20 will have so slid through the sleeve 29 that the spring fingers 62 and 63 will pass over the aforesaid projecting end portion of the sleeve 29. When the spring fingers 62 and 63 are arranged to extend vertically, which is to say, parallel to the ears 64 and 65, and the door D is swung to fully open position, then by reason of the aforesaid positioning of the attachment lug 39 and the length of the guide rod 20, the spring fingers 62 and 63 will pass over the ears 64 and 65 and thereupon clamp the sleeve 29 therebetween so as to hold the door D in the fully open position thereof. It will thus be seen that whenever the spring fingers 62 and 63 are arranged in vertical position as aforesaid and the door D is swung to fully open position, it is automatically retained in this fully open position until sufficient force is applied thereto to overcome the clamping effect of the spring fingers 62 and 63.

In order to insure that the spring fingers 62 and 63 will engage the ears 64 and 65 with sufficient tension to retain the door in open position until sufficient manual force is applied to overcome the clamping effect of the fingers 62 and 63, it is desirable that the tension of the spring fingers 62 and 63 be capable of such adjustment as to insure that the clamping effect thereof will be sufficient to resist wind pressure and the like on the door D to prevent undesired closing thereof. To this end a screw 66 is, in the present instance, freely passed through an opening in the spring finger 63 and the threaded end of this screw 66 is passed into a tapped opening in the spring finger 62. Then by manipulating the screw 66, the spacing between the curved gripping portions of the fingers 62 and 63 may be varied to thereby vary the tension that will be applied by these fingers on the ears 64 and 65 and the portion E. By reason of the adjustment thus afforded I am able to insure that the tension of the spring fingers 62 and 63 will at all times be sufficient to resist undesired closing of the doors D from the fully open position thereof.

Many times doors, such as those with which my novel door holder is adapted to be used, are equipped with a door closing means and in many instances it will be desirable that the door be closed by such door closing means even though the door is swung to the fully open position thereof which would ordinarily enable the spring fingers 62 and 63 to be effective to retain the door in this fully open position against the action of the normal door closing means. In those instances where it is not desired that the door be retained in fully open position and that it be responsive to the effect of the normal door closing means associated therewith and even in other instances where it is not desired that a door be retained in fully open position, even though it is not equipped with a door closing means, it is advantageous to so arrange the element 53, which includes the spring contact fingers 62 and 63, that the spring fingers may be rendered ineffective to automatically retain a door in fully open position. Therefore, the element 53 is rotatably mounted on the reduced circular portion 49 on the guide rod 20.

However, in order to insure that the element 53 may be accurately oriented so that the ears 64 and 65 will pass between clamping fingers 62 and 63 when automatic retention of the door in

fully open position is desired and also to insure that the fingers 62 and 63 may be disposed in an ineffective position whereat they will not automatically function to retain the door in fully open position, I mount the element 53 for but limited rotatable movement on the reduced circular portion 49. To this end and as best shown in Fig. 19, the flange 57 on the sleeve 56 is interrupted to thereby define shoulders 67 and 68 which are preferably spaced ninety degrees apart and, in a manner to be explained presently, the reduced circular portion 49 and the sleeve 56 are so arranged that when my novel door holder is used with a door hinged at the left as is the door D, Fig. 9, the shoulder 67 will be disposed in a horizontal position and the shoulder 68 will be disposed in a vertical position. Moreover, a lug 69 is provided on the face of the plate 54 disposed toward the flange 57 and this lug is arranged to be movable between the shoulders 67 and 68 so as to thereby limit the rotative movement of the element 53.

The arrangement is such that when the shoulder 68 is arranged to extend vertical and the lug 69 is engaged therewith, the spring fingers 62 and 63 are arranged in position to engage the ears 64 and 65 when the projecting end portion E of the sleeve 29 passes therebetween in the manner shown in Fig. 11 which is occasioned when the door as D is swung to fully open position illustrated in broken lines in Fig. 9. However, when the handle G which projects from the lower end of the plate 54 is grasped and the element 53 is turned on the reduced circular portion 49 so as to move the lug 69 into engagement with the horizontal shoulder 67, the spring fingers 62 and 63 are swung ninety degrees so that instead of being disposed in the vertical position shown in Fig. 11 in which they are effective to engage the ears 64 and 65, the fingers 62 and 63 are disposed in horizontal planes as illustrated in Fig. 12. When the spring fingers 62 and 63 are so disposed in horizontal planes and the door D is swung to fully open position, the projecting end E of the sleeve 29 passes therebetween but in this instance the aforesaid flat faces on this projecting end portion freely pass between the fingers 62 and 63 which therefore do not exert a clamping effect on the sleeve 29 and therefore when the door D is swung to fully open position illustrated in broken lines in Fig. 9, it is not automatically held in this position for, as stated, the flat faces of the projecting end portion of the sleeve 29 freely pass between the fingers 62 and 63, as shown in Fig. 12. Therefore, the normal door closing means effective on the door D may bring about closing thereof even when the door D is swung to fully open position.

It will be apparent, when the free end of the projecting end portion passes between the fingers 62 and 63 and engages the inwardly disposed face of the plate 54, that the spring 59 will be effective to dissipate the shock incidental to such engagement.

It is desirable that my novel door holder be capable of use with doors that are hinged at the left-hand or at the right-hand side thereof, and it is also desirable, for example as illustrated in Fig. 9, that my novel door holder be mounted in juxtaposition to a door as D. However, if the shoulders 67 on the flange 57 were always arranged in horizontal position, it would be necessary, when my novel door holder was secured to a door hinged at the right-hand side thereof, to turn the handle G on the plate 54 toward the

door as D rather than away from the door as is done when my novel door holder is attached to a door hinged at the left-hand side thereof and the shoulder 67 is arranged in a horizontal plane. One way of overcoming this would be to so arrange my door holder that it could be used only with a door hinged at the left-hand side thereof or only with a door hinged at the right-hand side thereof, but this would obviously be objectionable. Hence, I have so arranged my novel door holder that it may be used either with a door hinged at the left-hand side or at the right-hand side thereof, and to this end I have so arranged the sleeve 56 that it may be mounted in alternate positions depending upon whether my door holder is to be used with a door hinged at the left-hand side or at the right-hand side thereof.

Thus referring to Fig. 17 it will be seen that the outer end of the reduced circular end portion 49 of my novel door holder is provided with right-angularly related flat faces 70 and 71 which are so disposed with relation to the guide rod 20 that the flat face 70 projects downwardly. Furthermore, the bearing surface 58 in the sleeve 56 is provided with a flat face 72 that is complementary to the flat faces 70 and 71. Then when my novel door holder is to be used with a door that is hinged at the left-hand side thereof, the flat face 72 is engaged with the vertically extending flat face 71 which disposes the shoulder 67 in a horizontal plane and the shoulder 68 in a vertical plane. In this circumstance when the lug 69 is engaged with the shoulder 68, as shown in Fig. 14, the spring fingers 62 and 63 are arranged in vertical position, which is to say, in the position in which they will be effective to engage the ears 64 and 65. When, however, the handle G is grasped and the element 53 is turned so as to engage the lug 69 with the shoulder 67, as shown in Fig. 15, then the spring fingers 62 and 63 are so disposed that the flat faces of the projecting end portion E of the sleeve 29 will pass therebetween in the manner shown in Fig. 12. This arrangement, as explained hereinabove, is resorted to when the door is hinged at the left-hand side thereof as is the door D shown in Fig. 9.

When, however, my door holder is to be used with a door hinged at the right-hand side thereof, the castellated nut 61 is removed so as to enable the sleeve 56 to be withdrawn from the reduced circular portion 49 to thereby permit the flat face 72 to be disengaged from the flat face 71. When this is done, the flat face 72 may be engaged with the flat face 70 which results in the shoulder 67 being disposed in a vertical plane and the shoulder 68 being disposed in a horizontal plane, and in this instance the lug 69 is again disposed to be movable between the shoulders 67 and 68. In this instance, however, the lug 69 will be engaged with the shoulder 67 when the spring fingers 62 and 63 are to be effective to retain the door in open position in the manner above described. However, when the spring fingers 62 and 63 are to be rendered ineffective so as to permit the flat faces of the projecting end E of the sleeve 29 to freely pass therebetween in the manner shown in Fig. 12, the handle G is grasped and in this instance the element 53 is rotated ninety degrees in a direction opposite to the manner in which it is turned from the position shown in Fig. 14 into the position shown in Fig. 15 and in so doing the lug 69 engages the shoulder 68 which disposes the spring fingers 62

and 63 in ineffective position. It will be appreciated that when my novel door holder is used with a door which is hinged at the left-hand side thereof and the handle G is rotated from the position shown in Fig. 14 to the position shown in Fig. 15, it is turned away from the door. The handle G is also turned in a direction away from the door when the flat face 72 is engaged with the flat face 70 for in this instance my novel door holder will be used with a door which is hinged at the right-hand side thereof and in this instance it is necessary to turn the handle G clockwise, as viewed in Fig. 14, in order to render the fingers 62 and 63 ineffective as explained hereinabove.

There may be instances where it will not be necessary to resort to a friction grip between the guide rod as 20 and a button as 47 of fibrous material and in such instances it may be advantageous to so arrange the guide sleeve 29 that a prolonged clamping engagement may be effected between this guide sleeve and the guide rod 20. In instances such as this resort may be had to the arrangements illustrated in Figs. 7 and 8 where the guide sleeve 29a includes a boss 30a which is desirably secured to an attachment plate 39a in the manner shown, for example, in Fig. 10 and described hereinabove, it being understood that in this instance the attachment plate is secured to the jamb J in the same manner as that in which the attachment plate 39 is secured to such a jamb. In this instance, however, the boss 31 is supplanted by a pair of ears 73 and 74 and the lower face of the sleeve 29a is medially divided as indicated at 75, the ear 73 being disposed on one side of such medial division and the ear 74 on the opposite side. In an instance such as this, a thumb screw 76 is freely passed through the ear 73 and is threaded into a tapped opening provided in the ear 74. Normally the thumb screw 76 is so arranged relative to the ears 73 and 74 that the guide rod 20a may freely slide through the opening afforded therefor in the sleeve 29a. However, when the door with which this arrangement is used has been swung to a desired open position, the thumb screw 76 may be grasped and turned so as to draw the ears 73 and 74 toward each other to thereby reduce the width of the slot 75 and when this is done, the sleeve 29a effectively grips the guide rod 20a throughout the prolonged interengagement of these parts and in this way the door may be firmly secured in a partly open position. However, while the arrangement thus shown in Figs. 7 and 8 has the advantage that it is more economical than the arrangement shown in Fig. 3, there will be instances where it will be particularly advantageous to resort to the arrangement shown, for example, in Fig. 3 for the utilization of a button of fibrous material as the button 47 will insure against damage to a finished surface on the guide rod as 20 and is otherwise advantageous.

In Figs. 4, 9 and 20 I have illustrated an arrangement which may be utilized with a door holder of the kind hereinabove described to retain the door in fully closed position. To this end a substantially U-shaped bracket 77 is provided which has ears as 78 at the free ends of the limbs thereof and which extend substantially at right angles to such limbs which are adapted to be secured to the door D by having screws 79 or the like passed through apertures provided therein. As can best be ascertained from Figs. 4, 9 and 20, the bracket 77 is secured to the door D in such position as to lie closely adjacent to the

rod as 20 when the door D is in fully closed position.

The bight portion of the bracket 77 is preferably somewhat flattened to afford a bearing surface against which a finger 80 may be rested to be pivotally connected thereto by a rivet 81 or the like. A handle 82 in the present instance in unitary with the finger 80 and preferably the pivotal connection of the finger 80 and handle 82 to the bracket 77 is sufficiently tight that undesired movement of these parts relative to the bracket will be prevented.

The bracket 77 extends outwardly from the door D sufficiently to enable the handle 82 to be turned from the broken-line position thereof shown in Fig. 4 into the full-line position thereof and when the finger is disposed in this position, it is sized so as to lie in front of the rod as 20, and preferably the rod 20 will be so disposed with respect to the door D that the finger 80, when disposed in the full-line position, will either engage with the rod 20 or lie quite close thereto.

When the finger 80 is in the full-line position thereof shown in Fig. 4 and an attempt is made to move the door D from the fully closed position thereof, the rod 20 will so engage the finger 80 that movement of the door from the fully closed position thereof will be prevented. It will therefore be seen that an arrangement such as the bracket 77 and the finger 80 when arranged to cooperate with a rod as 20 may be utilized to prevent undesired movement of a door as D from the fully closed position thereof.

Furthermore, there will be instances where it will not be necessary to secure a door in positions intermediate the fully open and fully closed positions thereof as, for example, the doors to a garage or the like where it is necessary only to secure the doors in fully open position. In such an instance resort may be had to the arrangement shown in Fig. 13 where a bracket 26b is secured to a door as Db and which has an eyelet 24b pivotally mounted between the ears of the bifurcated lug 25b. In this instance a circular guide rod 20b is utilized but it will be understood that a guide rod polygonal in outline could be utilized, if desired.

In this instance, however, the guide sleeve 29b includes only a boss as 30b that is connected to the attachment plate 39b in the manner shown, for example, in Fig. 10. However, the sleeve 29b in this instance does not include a boss as 31 nor is it medially divided as at 75, Fig. 8. Also in this instance an arrangement like that illustrated, for example, in Fig. 10 is provided at the free end of the guide rod 20b so that an ear as 65b may cooperate with a spring finger as 63b to thereby be automatically effective to retain a door as Db in fully open position. It will be understood that while the parts provided at the ends of the guide rod 29b are not described in detail, these parts correspond to similar parts shown, for example, in Fig. 10, and where these parts appear in Fig. 13 they are designated by a reference character corresponding to that used, for example, in Fig. 10 but in Fig. 13 the suffix "b" is added to such reference characters.

Hereinabove I have described that a castellated nut 61 is mounted at the outer end of the guide rod 20 and such a nut is advantageously used where my door holder is to be associated with a door that also has a screen, storm or similar door associated therewith, for in such an instance the rounded end of the castellated nut will freely slide over the other door and the likelihood of

damage as a result of such sliding will therefore be mitigated. It will be understood, however, that if desired resort could be had to an ordinary nut rather than to the castellated nut that I have shown and described.

Hereinabove I have referred to my invention as being a door holder and while this is the primary purpose of my invention, it will be understood that it is equally applicable to use with other hingedly mounted members as, for example, casement windows, cabinet doors and the like, and it is therefore to be understood that the term "door" is used herein in a generic rather than in a strictly definitive sense.

Moreover, hereinabove I have referred to the cooperation of the end portion as E of the guide sleeve as 29 and the spring fingers as 62 and 63 being effective to automatically retain a door in fully open position. It will be recognized, however,

that there may be instances where it will be desirable to retain a door in some predetermined position rather than in the fully open position thereof, and hence reference to automatic retention of a door in fully open position is to be understood as being applicable to automatic retention of a door in a predetermined open position rather than strictly in the fully open position thereof.

In the foregoing description I have provided a novel door holder which may be arranged either to retain a door in positions intermediate the fully open or fully closed positions thereof and I have so arranged the door holder that such holding of the door may be manually effected.

Moreover, my door holder is so constituted and arranged that it will be automatically effective to retain a door in fully open position and in this respect my door holder may be so arranged as to only be effective to retain a door in fully open position or it may also embody manually operable means, referred to hereinabove, which are effective to retain the door in positions intermediate the fully open and fully closed positions thereof.

Furthermore, my novel door holder is so arranged that the means which are automatically effective to retain the door in fully open position may be manually rendered ineffective so as to enable, for example, door closing means associated with the door to function in the intended manner.

Additionally, the means which are so manually operative to render the automatic retention of a door in fully open position are so arranged that by making a simple adjustment this means may be used with a door that is hinged either at the right-hand or at the left-hand side thereof and still have such means so arranged that it will be movable in a direction away from the door.

Many other advantages of my novel door holder will be apparent from the foregoing description and in this respect, while I have illustrated preferred embodiments of my invention, it is to be understood that these are capable of variation and modification and I therefore do not wish to be limited to the precise details set forth but desire to avail myself of such changes and alterations as fall within the purview of the following claims.

I claim:

1. A door holder comprising a rod provided at one end with means for pivotal attachment to a door, a guide through which the rod slidably extends, means for mounting said guide swivelly on a door casing, the end portion of the rod be-

ing reduced to form a shoulder, a sleeve slidable on said reduced portion and having a flange at one end thereof, a spring coiled around the reduced end portion of said rod urging said sleeve toward said shoulder, stop means on the end of said reduced end portion against which the spring reacts, together with a pair of spring jaws disposed at opposite sides of the rod and connected by an integral portion fitted on the rod between said shoulder and said flange and rotatable about the axis of the rod, said jaws being normally engageable with holding abutments formed on opposite sides of the guide and positioned to be embraced by the jaws at the limit of opening movement of the door, and co-operating stop means on the flange and on the connecting member of the jaws respectively, permitting the latter to be rotated through a quarter turn about the axis of the rod to render the jaws inoperative with respect to said abutments, said coil spring providing friction for retaining the jaws at either position of adjustment.

2. A door holder comprising a rod provided at one end with means for pivotal attachment to a door and having a pair of clamping fingers thereon, a guide through which said rod is slid-able, means for pivotally connecting said guide to a jamb, a formed portion on said guide disposed to be engageable with the clamping fingers when said clamping fingers are disposed in a predetermined position on said rod and the door is moved to such an open position that the clamping means engage said formed portion to thereupon be effective to retain the door in such open position, said guide also having a sized portion thereon associated with said formed portion which is sized so as to be movable into association with said clamping fingers without having said clamping fingers exert a clamping effect thereon, and means connecting said clamping fingers to said rod for movement to and from said predetermined position thereon whereby said clamping fingers may be moved from said predetermined position into a position to cooperate with the sized portion on said guide so that when said sized portion is moved into association with said clamping fingers when said door is moved to an open position said clamping fingers will be ineffective to retain said door in such open position.

3. A door holder comprising a rod provided at one end with means for pivotal attachment to a door and having clamping means thereon, a guide through which said rod is slid-able, means for pivotally connecting said guide to a jamb, a formed portion on said guide disposed to be engageable with the clamping means when said clamping means is disposed in a predetermined position on said rod and the door is moved to such an open position that the clamping means engage said formed portion to thereby be effective to retain the door in such open position, means for retaining said clamping means on said rod and embodying spaced apart stops, and means on said clamping means movable between said stops whereby when said means is engaged with one of said stops said clamping means is disposed in said predetermined position and when such means is engaged with the other of said stops said clamping means is moved from said predetermined position to a position wherein the clamping means is ineffec-

tive to engage said formed portion and retain the door as aforesaid.

4. A door holder comprising a rod provided at one end with means for pivotal attachment to a door and having a pair of clamping fingers thereon, a guide through which said rod is slid-able, means for pivotally connecting said guide to a jamb, a formed portion on said guide disposed to be engageable with the clamping fingers when said clamping fingers are disposed in a predetermined position on said rod and the door is moved to such an open position that the clamping means engage said formed portion to thereupon be effective to retain the door in such open position, said guide also having a sized portion thereon associated with said formed portion which is sized so as to be movable into association with said clamping fingers without having said clamping fingers exert a clamping effect thereon, means for retaining said clamping fingers on said rod for rotative movement thereon and embodying spaced apart stops, and means on said clamping fingers selectively engageable with said stops whereby when such means is engaged with one of said stops said clamping fingers are disposed in said predetermined position and when such means are engaged with the other of said stops said clamping fingers are disposed in a position to cooperate with the sized portion on said guide so that when said sized portion is moved into association with said clamping fingers when said door is moved to an open position, said clamping fingers will be ineffective to retain said door in such open position.

5. A door holder comprising a rod provided at one end with means for pivotal attachment to a door and having clamping means thereon, a guide through which said rod is slid-able, means for pivotally connecting said guide to a jamb, a formed portion on said guide disposed to be engageable with the clamping means when said clamping means is disposed in a predetermined position on said rod and the door is moved to such an open position that the clamping means engage said formed portion to thereby be effective to retain the door in such open position, means connecting said clamping means to said rod for movement to and from said predetermined position thereon whereby said clamping means may be moved from said predetermined position to a position wherein the clamping means is ineffective to engage said formed portion and retain the door as aforesaid, and means included in the means connecting said clamping means to said rod that are constituted and arranged to enable said clamping means to be disposed on said rod for movement either in a clockwise or in a counterclockwise direction selectively to and from said predetermined position.

6. A door holder comprising a rod provided at one end with means for pivotal attachment to a door and having clamping means thereon, a guide through which said rod is slid-able, means for pivotally connecting said guide to a jamb, a formed portion on said guide disposed to be engageable with the clamping means when said clamping means is disposed in a predetermined position on said rod and the door is moved to such an open position that the clamping means engage said formed portion to thereby be effective to retain the door in such open position, means for retaining said clamping means on said

rod and embodying spaced apart stops, means on said clamping means movable between said stops whereby when said means is engaged with one of said stops said clamping means is disposed in said predetermined position and when such means is engaged with the other of said stops said clamping means is moved from said predetermined position to a position wherein the clamping means is ineffective to engage said formed portion and retain the door as aforesaid, and means for connecting said retaining means to said rod in alternately selectable positions to thereby dispose said spaced apart stops in selected positions and thereby enable said clamping means to be selectively moved either clockwise or counterclockwise into said predetermined position.

7. A door holder comprising a rod provided at one end with means for pivotal attachment to a door and having clamping means thereon, a guide through which said rod is slidable, means for pivotally connecting said guide to a jamb, a formed portion on said guide disposed to be engageable with the clamping means when said clamping means is disposed in a predetermined position on said rod and the door is moved to such an open position that the clamping means engage said formed portion to thereby be effective to retain the door in such open position, a bearing shoulder on said rod on which said clamping means is mounted to be rotatable thereon, a member retained in engagement with said clamping means and including spaced apart stops, a projection on said clamping means movable between said stops whereby when said projection is engaged with one of said stops said clamping means is disposed in said predetermined position and when said projection is engaged with the other of said stops said clamping means is moved from said predetermined position to a position wherein the clamping means is ineffective to engage said formed portion and retain said door as aforesaid.

8. A door holder comprising a rod provided at one end with means for pivotal attachment to a door and having clamping means thereon, a guide through which said rod is slidable, means for pivotally connecting said guide to a jamb, a formed portion on said guide disposed to be engageable with the clamping means when said clamping means is disposed in a predetermined position on said rod and the door is moved to such an open position that the clamping means engage said formed portion to thereby be effective to retain the door in such open position, a bearing shoulder on said rod having angularly related faces thereon and affording a bearing surface on which said clamping means is rotatably mounted, a member retained on said rod and having a face thereon selectively engageable with the angularly related faces on said bearing portion, said member having spaced apart stops thereon adapted to be disposed in a selected position when the face on said member is engaged with one of said angularly related faces and adapted to be disposed in another position when the face on said member is engaged with the other of said angularly related faces, and a projection on said clamping means disposed between said stops and movable in a clockwise direction between said stops to move said clamping means to and from said predetermined position when said stops are disposed in one of the aforesaid

positions and movable between said stops in a counterclockwise direction to move said clamping means to and from said predetermined position when said stops are disposed in the other of the aforesaid positions thereof, said clamping means being movable from said predetermined position to a position wherein this means is ineffective to engage said formed portion and retain said door as aforesaid.

10. 9. A door holder comprising a rod provided at one end with means for pivotal attachment to a door and having a pair of clamping fingers thereon, a guide through which said rod is slidable, means for pivotally connecting said guide to a jamb, a formed portion on said guide disposed to be engageable with the clamping fingers when said clamping fingers are disposed in a predetermined position on said rod and the door is moved to such an open position that the clamping means engage said formed portion to thereby be effective to retain the door in such open position, said guide also having a sized portion thereon associated with said formed portion which is sized so as to be movable into association with said clamping fingers without having said clamping fingers exert a clamping effect thereon, and means including a resilient portion connecting said clamping fingers to said rod for movement to and from said predetermined position thereon whereby said clamping fingers may be moved from said predetermined position into a position to cooperate with the sized portion on said guide so that when said sized portion is moved into association with said clamping fingers when said door is moved to an open position said clamping fingers will be ineffective to retain said door in such open position, said resilient portion being effective to dissipate the shock incidental to the engagement of the formed portion on said guide with said clamping fingers.
10. A door holder comprising a rod provided at one end with means for pivotal attachment to a door and having a pair of clamping fingers thereon, a guide through which said rod is slidable, means for pivotally connecting said guide to a jamb, a formed portion on said guide disposed to be engageable with the clamping fingers when said clamping fingers are disposed in a predetermined position on said rod and the door is moved to such an open position that the clamping means engage said formed portion to thereby be effective to retain the door in such open position, said guide also having a sized portion thereon associated with said formed portion which is sized so as to be movable into association with said clamping fingers without having said clamping fingers exert a clamping effect thereon, means connecting said clamping fingers to said rod for movement to and from said predetermined position thereon whereby said clamping fingers may be moved from said predetermined position into a position to cooperate with the sized portion on said guide so that when said sized portion is moved into association with said clamping fingers when said door is moved to an open position said clamping fingers will be ineffective to retain said door in such open position, and means for adjusting the relative position of said clamping fingers to thereby insure effective engagement thereof with said formed portion so as to insure retention of the door in open position.
